ATTORNEY

UNITED STATES PATENT OFFICE.

ARTHUR ATWATER KENT, OF PHILADELPHIA, PENNSYLVANIA.

MASSAGE-MACHINE.

978,031.

Specification of Letters Patent. Patented Dec. 6, 1910.

Application filed May 21, 1908. Serial No. 434,087.

To all whom it may concern:

Be it known that I, ARTHUR ATWATER KENT, a citizen of the United States, and a resident of Philadelphia, county of Philadelphia, State of Pennsylvania, have invented certain new and useful Improvements in Massage-Machines, of which the following is a full, clear, and exact disclosure.

10 My invention relates to massage machines and more particularly to that class of machines in which a movement of gyration is imparted to the massage pad, cap or other instrument which is adapted to be applied 15 to the part of the body of the person being treated.

The object of my invention is to provide a machine, of the type above referred to, which is simple but efficient, and of few 20 parts and which is not easily gotten out of order.

A further object is to provide positive and efficient means for adjusting or varying the degree or amplitude of the stroke or movement of the massage instrument to effect a gentle or a more violent massage as may be desired and to provide for such adjustment without stopping the machine by the simple movement of a regulating member.

30 A further object of my invention is to vary the amplitude of the stroke or vibration without changing the relative position or distance between the massage instrument and the shell or casing or operating mechanism contained therein.

Other objects of my invention will appear in the specification and claims below.

In the drawing forming a part of this specification and in which the same reference characters are employed to designate the same parts throughout the various views, Figure 1 is a longitudinal sectional view on the line I—I of Fig. 2 and Fig. 2 is a plan view of my device.

45 Within the main casing 1 is a small motor (not shown) mounted in any suitable manner upon a driving shaft 2 the end of which projects for a short distance into the extension 3 of the casing. The said extension 50 is preferably cylindrical in shape and is of a size which can be conveniently grasped by the operator to guide or carry the machine as desired. The said end of the shaft is preferably slotted as at 4 and within said 55 slot upon a pivot pin 5 extending through

and transversely to the axis of the said shaft is pivoted a bell-crank lever 6 having one arm 7 extending from said pivot substantially in the direction of the sides of the said cylindrical extension 3 and the other arm 8 similarly extending substantially in the direction of the axis of the said shaft 2.

The end of the arm 8 of the bell-crank lever 6 is preferably provided with a slot 9 within which one end of a swiveled connecting member 10 is pivoted on a pivot pin 11 which extends substantially parallel to the pin 5. The other end of the said member 10 is provided with a smooth cylindrical bore 12 within which the inner end of the pivoted massage rod 13 is free to slide. The member 10 thus provides a sleeved or swiveled connection between the end 8 of the bell-crank lever 6 and the massage rod 13.

The massage rod 13 is preferably fulcrumed upon a ball and socket joint in the following manner. Between the ends of the massage rod 13 is secured a ball 14, 60 through which said rod 13 passes and to which it is rigidly fastened by the set-screw 15. The outer end of the cylindrical extension 3 is provided with a hole or opening 16 the outside edges of which are preferably 65 concaved to fit smoothly against the surface of the ball 14. The inner end of said opening 16 is larger in diameter than the diameter of the said rod 13 and is preferably enlarged or flared inwardly as plainly shown 70 in Fig. 1 of the drawings to give the rod 13 sufficient clearance when the same is given a gyratory motion. The ball 14 may be retained upon its concave seat at the outer end 75 of the opening 16 by a cap 17 threaded 80 into a recess 18 in the said extension 3 arranged concentrically with the hole or opening 16, the inner end of said cap 17 when properly adjusted bearing lightly against the said ball 14. The cap 17 is also provided 85 with an axial hole or opening 19 through which the massage rod 13 passes and the said opening 19 is preferably tapered or flared outwardly to give sufficient clearance 90 to the massage rod 13. The ball 14 is preferably provided with a radially extending pin 20 the outer end of which extends into a slot 21 in the end of the extension 95 arranged substantially parallel to the axis of the shaft 2.

100 105 110

On the outer end of the massage rod 13 is mounted in any suitable manner a massage cup, pad or other instrument 22 adapted to be applied to the body of the person being treated.

5 Within the tubular extension 3 of the casing is the adjusting member which comprises a ring or sleeve 23 slidably fitted within the said extension. The said ring is provided 10 with an annular groove 24 on its inner surface. A suitable pin or set screw 25 is fastened to the ring and passing through a suitable slot 26 in the said extension provides a means to enable the operator to move the 15 ring both longitudinally and rotatably within the said extension. The end 7 of the bell-crank lever 6 extends into the groove 24 and revolves within the same when the shaft 2 is rotated and the end of the said arm 7 20 preferably terminates in a bell or sphere 27 the diameter of which is substantially equal to the width of the groove 24. I prefer to arrange the slot 26 in the extension 3 inclined to the axis of the said extension so 25 that a considerable movement of the pin or set screw 25 along the slot will cause the ring 23 to travel but a slight distance parallel to the axis of the driving shaft 2.

The operation of my device is as follows: 30 The shaft 2 being rotated from the motor within the casing 1, the bell-crank lever 6 is also rotated with it and the ball or sphere 27 on the arm 7 of the said bell-crank lever revolves around the axis of the shaft with 35 in the groove 24. The other end 8 of the bell-crank lever also revolves around the axis of the shaft and imparts to the massage rod 13 a gyroscopic movement on account of the swiveled connection between the end 8 40 of the bell-crank lever and the inner end of the massage rod. It should be noted that the inner end of the massage rod should not engage the bottom of the opening or bore 12. The massage rod 13 is prevented from 45 rotating by reason of a pin and slot connection 20-21 between the ball 14 and the end of the casing. To adjust the degree or amplitude of the vibration or gyration of the massage rod 13 the pin or set screw 25 50 is adjusted at various positions in the slot 26. When the pin is in that end of the slot nearest the motor the end 7 of the bell-crank lever 6 will be located to the right of the position shown in Fig. 1 and the other end 8 55 of the bell-crank lever will be brought in substantial alignment with the axis of the shaft. The bell-crank lever will then be rotated but will impart no movement whatever to the massage rod. As the pin is how- 60 ever adjusted toward the other end of the slot the end 7 of the bell-crank lever will be moved to the left of the position shown in Fig. 1 and the other end of the bell-crank lever will be moving outwardly from the 65 axis of the shaft. The swiveled connection

permits the sleeve 10 to turn upon the inner end of the rod 13 but the said end will be moved in a circular path and the massage instrument at the other end of the massage rod will be given a similar movement.

76

While I have described one form or embodiment of my invention I do not wish it to be construed as being limited to the exact structure shown, inasmuch as various changes and arrangements may be made 75 without departing from my invention so long as such changes are within the scope of the appended claims.

Having thus described my invention, what I claim and desire to protect by Letters Patent of the United States is:—

80

1. In a massage machine a massage rod, a driving shaft, a lever pivoted to said shaft and having one end connected to said massage rod and the other end extending outwardly from the axis of said shaft and means engaging said outwardly extending end of said lever to adjust the other end of said lever to varying distance from the axis of rotation of said shaft.

85

2. In a massage machine a massage rod a driving shaft, a bell-crank lever pivoted to said shaft intermediate the ends of said lever and means engaging one end of said lever to adjust the other end of said lever to varying 95 distances from the axis of rotation of said shaft and swiveled means for connecting said last mentioned end of said lever with said massage rod.

90

3. In a massage machine, a driving shaft, 100 a bell-crank lever, pivoted to said shaft on an axis transverse to the axis of rotation of said shaft, a sliding member movable in a direction parallel to said shaft and having a circular groove co-operating with one end 105 of said lever and a massage rod swiveled to the other end of said lever.

100

4. In a massage machine a driving shaft, a bell-crank lever pivoted between its ends to said shaft on an axis transverse to the axis 110 of said shaft, a massage rod swiveled to one end of said lever, means to guide the other end of said lever in a circular path when said shaft is rotated, said means being slideable in a direction parallel to said shaft.

115

5. In a massage machine, a driving shaft, a bell-crank lever pivoted between its ends to said shaft on an axis transverse to the axis of said shaft, a massage rod swiveled to one end of said lever, a ring adapted to 120 guide the other end of said lever in a circular path when said shaft is rotated, said ring being slideable in a direction substantially parallel to said shaft.

120

6. In a massage machine, a driving shaft, 125 a bell-crank lever pivoted on said shaft on an axis transverse to the axis of rotation of said shaft, a massage rod operatively connected to one end of said lever, a ring surrounding said shaft and operatively engag- 130

ing, the other end of said lever and means to adjust said ring in different positions parallel to said shaft.

7. A massage machine, a driving shaft, a lever pivoted to said shaft intermediate the ends of said lever on an axis transverse to the axis of rotation of said shaft, a massage rod operatively connected to one end of said lever and means engaging the opposite end 10 of said lever to adjust the ends of said massage rod to a pre-determined distance from the axis of said shaft.

8. In a massage machine, a driving shaft, an adjustable member having a groove 15 concentric with the axis of said shaft, a member pivoted to said shaft and rotated thereby and having a portion extending into said groove and a massage rod operatively connected to said pivoted member.

20 9. In a massage machine, a driving shaft, an adjustable member having an annular groove, a member pivotally connected to said shaft and rotated thereby and extending into said groove, and a massage rod slid- 25 ingly connected to said pivoted member.

10. In a massage machine, a pivoted massage rod, a driving shaft, a member pivoted to said shaft and slidably connected to said massage rod, said pivoted member extend- 30 ing outwardly from the axis of said shaft, and means engaging said outwardly extend-

ing portion of said member, to adjust the connected end of said massage rod to pre-determined distances from the axis of rotation of said shaft.

11. In a massage machine, a driving shaft, a member having an annular groove concentric with the axis of said shaft, a lever pivoted to said shaft on an axis transverse to the axis of rotation of said shaft and having one end extending into said groove, means to adjust said member in a direction substantially parallel to the axis of said shaft and a massage rod operatively connected to the opposite end of said lever. 40 45

12. In a massage machine, a driving shaft, a lever pivoted to said shaft on an axis transverse to the axis of rotation of said shaft, a member movable in a direction substantially parallel with the axis of said shaft and having a circular groove in which one end of said lever is adapted to revolve and a massage rod operatively connected to the opposite end of said lever. 50

In witness whereof I have hereunto set 55 my hand this thirteenth day of May A. D., 1908.

ARTHUR ATWATER KENT.
